UNITED STATES PATENT OFFICE.

CHARLES E. PATTERSON, OF JACKSONVILLE, ILLINOIS.

BACK REST FOR INVALID BEDS.

Original application filed April 21, 1926, Serial No. 103,542. Divided and this application filed August 17, 1926. Serial No. 129,828.

This invention relates to invalid beds and more especially to a back rest or lift for use in connection therewith, one of the objects being to provide a structure of this character 5 which is yieldingly supported and by the use of which a patient can be maintained comfortably in a sitting or reclining posture.

This application is more especially a division of an application filed by me on April 10 21st, 1926, Serial No. 103,542, and the invention resides in the combination and arrangement of parts and in the details of construction hereinafter described and claimed, it being understood that changes in the precise 15 embodiment of the invention herein disclosed may be made within the scope of what is claimed, without departing from the spirit of the invention.

In the accompanying drawings the preferred form of the invention has been shown.

In said drawings,

Figure 1 is a plan view of a portion of a bed structure having the present improvements thereon.

25 Figure 2 is a side elevation thereof.

Figure 3 is a side elevation on an enlarged scale showing the yielding means employed for controlling the downward movement of the back rest.

30 Referring to the figures by characters of reference 18 designates a portion of a bed structure on which a patient is adapted to rest. Extending from the sides of this structure 18 are upstanding brackets 36 to 35 which are pivotally connected heads 37 each of which has an arcuate flange 38 along the bottom thereof. An arcuate series of apertures 39 is provided in each head and any one of these apertures is adapted to receive 40 a pin 40 extending inwardly from the bracket 36, thus to hold the head against rotation about its pivot 41. A steel cable 42 is secured at one end to the forward portion of each of the arcuate flanges 38 and is attached 45 at its other end to a spring 43. This spring is adjustably connected by a turnbuckle 44 or the like to the end portion 21 of the structure 18. This spring 43 obviously exerts a continuous pull through the steel cable 42 upon the arcuate portion 38 of the head 37. Consequently when a pin 40 is removed from each head 37, the said disks or

heads 37 will be rotated by the springs. These disks or heads 37 are provided with sockets 45 in which are seated the lower ends of the sides 55 of a frame 46 forming a part of a back rest. The sides of this frame are connected by an endless belt 47 which fits transversely around the frame. This belt can be easily slipped on or off of the frame as will be 60 apparent by referring to Figure 2. Obviously when the pins 40 are removed the frame will swing upwardly under the action of the springs 43 so as to afford a comfortable back rest which will adjust itself automatically to the patient. After the back rest has been brought to a desired position the pins 40 can be inserted so as to prevent further movement. When not in use the back rest can be swung downwardly between the 70 sides of the structure 18 and there held by inserting the pins 40 in the proper apertures 39. By means of turnbuckles 44 the tension of the springs can be regulated.

What is claimed is:

An invalid bed including a supporting structure, brackets fixedly connected to opposite sides of said structure, heads lapping the brackets, pivotal connections between the heads and brackets, a socket portion 80 radiating from each head, a frame having its sides insertible at one end into the socket portions, there being a series of apertures within each bracket and head, a fastening pin inserted into selected apertures to hold 85 the heads against rotation relative to the brackets, an arcuate flange extending laterally from one of the heads, a spring, a flexible connection between one end of the spring and that end of the flange remote from the 90 spring, thereby to wind upon the flange when the frame is pressed in one direction 95 away from normal position and to unwind therefrom to move the frame back to normal position when relieved from pressure, and adjustable means for anchoring the other end of the spring to the supporting structure, the tension of the spring being such as to exert a constant pull upon the peripheral portion of the head thereby to yieldingly 100 support the frame in an upstanding position.

In testimony that I claim the foregoing as my own, I have hereto affixed my signature.

CHARLES E. PATTERSON.
